UNITED STATES PATENT OFFICE.

HUGH W. PRETTYMAN, OF INWOOD, WEST VIRGINIA.

MOTION-PICTURE ARC LAMP.

Application filed June 21, 1921. Serial No. 479,358.

To all whom it may concern:

Be it known that I, HUGH W. PRETTYMAN, citizen of the United States, residing at Inwood, in the county of Berkeley and State 5 of West Virginia, have invented certain new and useful Improvements in Motion-Picture Arc Lamps, of which the following is a specification.

This invention relates to an improved 10 motion picture arc lamp and has as one of its principal objects to provide a construction wherein the carbons, in addition to the usual adjustments provided therefor, may also be axially rotated for maintaining 15 the proper angle between the craters of the carbons at their confronting ends.

A further object of the invention is to provide a lamp wherein, by axial rotation 20 of the carbons, increased efficiency of the arc may be obtained and wherein through turning of the carbons the length of service thereof may be prolonged.

And the invention has as a still further object to provide a lamp well adapted for 25 a wide range of use and wherein the carbons may be readily mounted in position and as easily removed.

Other and incidental objects will appear hereinafter.

30 In the drawings:

Figure 1 is a side elevation of my improved lamp, the lamp house being shown in section,

35 Figure 2 is a top plan view of one of the carbon holders employed, parts being broken away and shown in section,

Figure 3 is a sectional view on the line 3—3 of Figure 2, looking in the direction of the arrows,

40 Figure 4 is a bottom plan view particularly showing one of the clamps of the carbon holders.

Figure 5 is a fragmentary section showing a slight modification of the invention,

45 Figure 6 is a detail bottom plan view of the carbon holder shown in Figure 5, and

Figure 7 is a fragmentary section showing a further slight modification of the invention.

50 As previously intimated, the present invention seeks to provide a means whereby the carbons of a motion picture arc lamp may be axially rotated and in order to clearly bring out the function and operation 55 of the structure employed I have shown the invention in connection with certain con-

ventional parts of an ordinary arc lamp of the character indicated. The importance of maintaining a proper angle between the craters of the carbons is well known since the realization of the greatest efficiency from 60 the lamp is dependent upon this detail and while the usual feeding of the carbons serves to bring the confronting ends of the carbons closer together still, such feeding 65 fails to correct the condition brought about by wasting of the carbons at the sides of the craters thereof. The present invention, therefore, aims to overcome the disadvantages 70 of the usual lamp in the respects noted and, at the same time provide a construction which may be embodied in practically all motion picture arc lamps as now in common use.

Referring to Figure 1, I have shown a lamp house 10 and upstanding within the lamp house is a bracket 11 provided at its upper end with a head 12. Slidably mounted upon this head are companion rack bars 13 between which is interposed a pinion 14 upon an operating shaft 75 15. At its outer end this shaft is provided with a hand wheel 16 which may be turned, as will be readily appreciated, for coincidentally shifting the rack bars longitudinally and, as shall presently appear, feeding the carbons of the lamp. All of this structure is conventionally shown, and while I have illustrated only the feeding adjustment still, it is to be understood that the present invention may be embodied in motion picture arc lamps having not only a feeding adjustment but also all of the other adjustments usually provided in connection with lamps of this character.

In carrying the invention into effect, I 95 employ carbon supporting arms 17 secured at their inner ends, as shown in Figure 2, to the outer ends of the rack bars 13 by bolts 18, insulating bushings 19 being arranged to surround the bolts for insulating the arms with respect to said bars. Integrally formed on the arms at their outer ends are rings 20 at the lower edges of which are inwardly directed annular flanges 21 and upstanding from the rings at the junction of the arms therewith are bosses 22. Diametrically opposite these bosses the rings are further provided, as best shown in Figure 3, with bosses 23. Snugly but rotatably fitting within the rings are discs 24 seating flat against the flanges 21 to be rotatably supported thereby 100 and upstanding from the peripheries of said 105 110

disks are beveled gear rings 25. The disks are provided axially with openings 26 adapted to freely receive the usual carbons therethrough, as conventionally shown in Figure 1 at 27 and 28 respectively, and mounted upon the disks at their lower sides are carbon holding clamps for rigidly connecting the carbons with the disks. Each of these clamps includes, as best shown in Figures 3 and 4, a fixed clamp member 29 and a coacting pivoted clamp member 30. At their inner ends, the clamp members are formed with mating lugs 31 and extending through the disk 24 and through said lugs is a pin 32 pivotally supporting the clamp member 30. Extending through the disk and through the outer end portion of the clamp member 29 is a second pin 33 so that, as will be seen, the pins 32 and 33 will hold the clamp member 29 against movement while the clamp member 30 may be swung with respect thereto. Pivoted upon the clamp member 29 at its outer end is a clamping bolt 34 which is preferably equipped with a wing nut, and formed in the outer end of the clamp member 30 to freely receive said bolt is a slot 35. Thus, as will now be seen, after the carbons 27 and 28 have been projected through the disks 24, the clamp members 30 of the carbon holding clamps may be swung to confront the clamp members 29 when, by adjusting the nuts upon the bolts 34, the clamps will be caused to securely grip the carbons for firmly connecting the carbons with the disks. At the same time, the carbons may be readily removed when desired. In this connection it may be observed that the carbon supporting arms are disposed at an angle with respect to each other for sustaining the carbons 27 and 28 in proper angular relation.

Journalized through the bosses 22 of the arms 17 are operating shafts 36 in which are interposed universal joints 37 each comprising a coupling block 38 of suitable insulating material. These blocks serve, of course, to insulate the inner and outer sections of the shafts with respect to each other and, as shown in Figure 1, the shafts are arranged to extend through the lamp house 10 and are equipped with hand wheels 39. Fixed to the inner ends of said shafts are beveled pinions 40 coacting with the gear rings 25 of the disks 24 and mounted upon the bosses 23 of the rings 20 to ride against said gear rings are overhanging spring detents 41. Upstanding from the arms 17 are binding posts 42 to which suitable leads may be connected for completing a circuit through the carbons.

As will now be appreciated in view of the preceding description, the shafts 36 may be turned for rotating the disks 24 and consequently axially rotating the carbons 27 and 28. Accordingly, either of said carbons may, as necessity may demand, be adjustably

rotated axially with respect to the other of said carbons for maintaining the proper angle between the craters at the confronting ends of the carbons, the detents 40 serving to lock the carbons in adjusted position. As will be seen, this axial rotation of the carbons will in no wise interfere with the feeding of the carbons nor, in fact, will said adjustment interfere with the lateral, vertical or forward and rear adjustment of the lamp. Since the carbons are carried by the rack bars 13, feeding of the carbons may, of course, be accomplished by simply turning the shaft 15.

In Figures 5 and 6 of the drawings, I have illustrated a slight modification of the invention. In these figures, one of the carbon supporting arms is indicated at 17', the ring thereon at 20' and the flange of said ring at 21'. An operating shaft is indicated at 36' and the pinion upon said shaft at 40'. Snugly but rotatably fitting through said flange is a sleeve 43 provided at its upper end with an overhanging beveled gear ring 44 seating flat against the flange 21' and rotatably supporting the sleeve the pinion 40' coacting with said gear ring whereby the sleeve may be rotated. Threaded through the sleeve below the ring 20' is a plurality of radially disposed clamp screws 45 upon the inner ends of which are swiveled arcuate clamping heads 46 adapted to grip a carbon, as conventionally illustrated at 47, therebetween. Thus, when the sleeve 43 is turned, the carbon will be axially rotated. Otherwise this modified structure is identical with the preferred construction and provides a very convenient means of mounting the carbons of the lamp.

In Figure 7 of the drawings, I have illustrated a still further modification of the invention wherein I employ a sleeve 48 provided at its upper end with a disc having a gear ring 49 corresponding to the gear ring 44 of the prior modification and formed in the inner face of the sleeve near its lower end are concave channels 50. Threaded within the sleeve at its upper end is a tubular nut 51 and pivotally connected to the lower end of said nut are clamping members 52, the free ends of which are adapted to ride in said channels. As suggested, the nut is adapted to loosely receive a carbon therethrough, as conventionally shown at 53 and, as will now be clear, the nut may be adjusted within the sleeve 48 for riding the clamping members 52 downwardly within the sleeve into binding engagement with the carbon. Otherwise, this modified structure is identical with preferred form of the invention and is suggestive of the manner in which various minor variations in the structure may be made. I accordingly reserve the right to all such variations as may fall within the spirit of the appended claims.

Having thus described the invention, what is claimed as new is:

1. In an arc lamp, a rotatable disc, a sleeve extending from the disc and provided at its inner side with concave channels, a tubular nut threaded into the sleeve, and clamping members pivoted upon the nut to ride at their free ends in said channels, the nut being adapted to receive a carbon there-through and being adjustable for shifting the clamping members in said channels to engage and clamp the carbon.
2. In an arc lamp, an arm provided at one end with a ring having an inwardly directed annular flange at its lower edge, a disc rotatably seated upon said flange and provided with a peripheral upstanding gear ring revolvably fitting in said first mentioned ring, the disc being apertured to receive a carbon, a clamp including coacting pivoted members to engage and hold the carbon, and a pinion mounted to coact with said gear ring for rotating the disc.
3. In an arc lamp, an arm provided at one end with a ring having an inwardly directed annular flange at its lower edge and formed at its upper edge with a boss, a disc rotatably seated upon said flange and provided with a peripheral upstanding gear ring revolvably

fitting in said first mentioned ring, the disc 30 being apertured to receive a carbon, a clamp including coacting pivoted members to engage and grip the carbon, a shaft journaled through said boss, a pinion carried by said shaft to coact with said gear ring for rotating 35 the disc, and a spring detent mounted upon the former ring to coact with the teeth of said gear ring for locking the disc when rotated.

4. In arc lamp, the combination of a casing, a bracket upstanding therein, oppositely extending rack bars slidable upon the bracket, manually operable means extending outside of the casing for shifting said bars simultaneously, arms carried by said bars and provided with rings, discs journaled in said rings and provided with gear rings, the discs being apertured to receive carbons, means carried by the discs to engage and hold the carbons, and flexible shafts extending outside of the casing and provided at their inner ends with pinions to coact with said gear rings whereby the latter shafts may be manually turned for rotating said discs 50 selectively.

In testimony whereof I affix my signature.

HUGH W. PRETTYMAN. [L. s.]
